OIL BURNING STOVE

Cyril Lewis Tilburn, Shanghai, China

Application July 2, 1934, Serial No. 733,477
In Great Britain July 31, 1933

4 Claims. (Cl. 126—44)

This invention relates to cooking and like stoves heated by oil or gas and has for its object to provide an improved construction and arrangement of the kind wherein combustion gases from a burner or series of burners pass around a number of cooking chambers or vessels before making their exit from the casing of the stove through a chimney or exit flue.

The present invention consists in a cooking or like stove wherein a combustion chamber is provided having therein a perforated partition or baffle disposed between two burners or sets of burners, the portions of the said chamber at both sides of said partition being in communication with passages surrounding a series of ovens.

Reference will now be made to the accompanying drawings which illustrate by way of example a construction according to the invention and in which:

Fig. 1 is a plan view of a stove constructed according to this invention.

Fig. 2 is a longitudinal vertical section taken on the line A—A of Fig. 1.

Fig. 3 is a vertical cross section taken on the line B—B of Fig. 1 and

Fig. 4 is a further vertical cross section taken on the line C—C of Fig. 1.

In the construction illustrated, a stove is shown which comprises a substantially rectangular casing 1 having combustion or burner chambers 2 and 2a formed at its ends. Between the burner chambers are disposed two rows of ovens or cooking chambers 3, 3a and 3b and 4, 4a and 4b, and vertical and horizontal passages 6, 7 and 14 and 6a, 7a and 14a which enable the gases of combustion to pass around the ovens. The gases from the burner chambers 2 and 2a make their exit through outlets 8 and 8a respectively at the top of the inner sides of these chambers, and the gases finally leave the stove through a flue or chimney 9 which communicates with all the combustion gas passages 6, 7 and 14 and 6a, 7a and 14a. The burner chambers 2 and 2a at the ends of the stove are divided by slotted or otherwise perforated refractory partitions or ignition walls 10, and burners 11 are disposed at the outer ends of these chambers in positions remote from the said partition 10. The gases of combustion leaving the combustion chamber 2 pass through the outlets 8 into the passages 7 above the ovens 3a and 4a, the gases being prevented from passing to the remaining ovens owing to the interposition of partitions 13 in the vertical passages 6 immediately beyond the ovens 3a and 4a. These partitions extend downwardly through

passages or spaces 14 which extend beneath these ovens and which have outlets 15 at their ends communicating with flues 16 separated by a fire brick partition 12 communicating directly with the interior of the chimney 9. To prevent return of the gases from the passages 14 to the combustion chamber 2 through the openings 8, the upper end of the vertical passage 6 nearest the said chamber is closed by a baffle 25.

The combustion chamber 2a communicates 10 with the vertical and horizontal passages 6a, 7a and 14a around the ovens 3, 3b, 4 and 4b, through the outlets 8a, the passages around the oven 3b being capable of separation from those around the oven 3 and the passages around the oven 4b being capable of separation from those around the oven 4 by means of independently operable dampers 17 which thus enable the ovens 3 and 4 only to be used when required. The space separating the ovens 3 and 3b from the ovens 4 and 4b is also divided by a firebrick partition 12a, and the combustion gases after passing around the passages 6a, 7a and 14a are exhausted to the chimney 9 through outlets 15a and flues 16a similar to the flues 16. This chimney is divided 20 as shown in Figure 1 into four parts by partitions 18 crossing each other at right angles, each part of the chimney communicating with a separate exhaust passage, that is to say, two sections of the chimney respectively receive the exhaust 25 from the ovens 3a and 4a through the outlets 15 and separated flues 16 whilst the other two sections receive exhaust respectively from the ovens 3 or 3 and 3b and 4 or 4 and 4b, according to the positions of the dampers 17, through the 30 outlets 15a and separated flues 16a. Each section of the chimney is provided with a separate control damper the position of which is shown by indicators 19 on the exterior of the chimney and which enable the draught around the various 35 ovens to be regulated.

The dampers 17 are also provided with external operating handles 20 and the operation of either of these dampers closes one of the passages 7a in such a manner that the gases are 40 compelled to pass downwards through the passages 6a between the sides of the ovens 3 and 3b and 4 and 4b respectively.

The top of the stove and of the combustion chambers consists of a number of removable 50 plates 21 to facilitate cleansing whilst the ovens are provided with doors 22 hinged at their lower ends at 23 and adapted to open against resilient checking devices 24 which operate to prevent breakage due to sudden opening of the oven doors. 55

Air to support combustion in the chambers 2 and 2a is admitted through passages 26 formed at the outer ends of the base of each chamber and provided with a slidable plate 27 for controlling the draught. Above each burner is disposed a baffle 28 which assists in deflecting the flame onto the partition 10 and prevents the combustion products from passing directly through the outlet 8 without impinging on the 10 said partition.

In operation the two burners 11 (or sets of burners) in the ends of each of the combustion chambers 2 and 2a produce flames impinging one on each side of the respective partition 10, a very 15 intense heat being thereby concentrated on the partition to assist in effecting complete combustion of the fuel. When, however, the intense heat produced by the two burners in the combustion chamber 2 is not required and one burner 20 only is employed, a portion of the gases from one end or part of this combustion chamber will pass through the partition 10 and will ultimately be distributed through the outlets 8 to the passages surrounding the ovens 3a and 4a. 25 Similarly when one burner only is operative in the combustion chamber 2a, the hot combustion gases will circulate around the ovens 3, 3b, 4 and 4b, or if the dampers 17 are closed around the ovens 3 and 4 only. It is to be understood 30 that additional dampers may also be employed so that only one of said ovens is heated or to enable the ovens 3 and 3b or 4 and 4b to be used as a unit.

I claim:—

35 1. A stove of the class described having a combustion space, a vertical, refractory perforated ignition wall dividing said space into a plurality of chambers, spaced apart ovens, separate passages for conducting heated gases for heating 40 said ovens, said passages communicating with said chambers on opposite sides of said ignition

wall, and a fluid fuel burner positioned in each chamber to direct flame against said ignition wall whereby one burner may be used to heat all ovens or all burners may be used.

2. A heating device of the class described having a combustion space, a perforated ignition wall dividing said space into a plurality of chambers, separate passages each on a different side of said ignition wall for conducting heated gases from the separate chambers, and a fuel burner 10 positioned in each chamber to direct flame toward said ignition wall whereby one burner may be used to heat both passages or all burners may be used.

3. A stove of the class described having a combustion space, a vertical, perforated refractory ignition wall dividing said space into a plurality of chambers, ovens at one side of said space in spaced relation, means providing separate heating flues for said ovens having portions located 20 in the space between said ovens and separately communicating with said chambers on opposite sides of the ignition wall, and a fluid fuel burner positioned in each chamber to direct flame against said ignition wall whereby one burner may be 25 used to heat all ovens or all burners may be used.

4. A stove of the class described having oven means in spaced apart relation, a refractory partition in the space between said oven means providing heating flues for conducting heated gases 30 for heating said ovens, a combustion space beyond one end of said oven means having a perforated ignition wall substantially in line with said partition dividing the second mentioned space into two chambers communicating on opposite sides 35 of the partition with separate passages, and a fluid fuel burner positioned in each chamber to direct flame against said ignition wall whereby one burner may be used to heat all ovens or all burners may be used.

CYRIL LEWIS TILBURN.
